DENSIFYING MILL

Francis R. Murphy and Ray H. Bebout, Toledo, Ohio, assignors, by meane assignments, to Libbey-Owens-Ford Glass Company, a corporation of Ohio

Application March 10, 1942, Serial No. 434,074

4 Claims. (Cl. 18—10)

This invention relates to apparatus for densifying, and more particularly to a machine for densifying or compacting fusible powdered materials such as molding compositions.

Molding compositions, whether thermoplastic or thermo-setting, may be supplied to users in various colors, and often have varying ingredients, such as different plasticizers, to adapt the molding compositions for different types of molding operations. The ingredients of a molding composition are usually intermixed by grinding them together to a fine powder in a ball mill.

The resulting finely powdered mixture is very difficult to handle in molds because of its fluffy character and because of its high air content. It is difficult to get a sufficient weight of the powder into a mold, and air or other gas contained in the powder may become trapped and form blisters, voids or other flaws in the molded article.

It is therefore customary to subject the finely powdered mixture to a densifying operation. The powder may, for example, be placed in a kneading device in which it is warmed so that it becomes plastic and is kneaded to expel air and other gases and form a homogeneous dense mass. After it has been thus kneaded, it is put through a grinder to reduce the mass to granular form.

The usual densifying device must be charged with individual batches of powder and, of course, discharges the densified material in batches.

It is an object of this invention to provide a machine for densifying fusible powdered material in a continuous operation.

It is a further object of this invention to provide a machine which will continuously densify fusible powdered material into a mass having characteristics which will permit subsequent granulation of such mass to be more easily accomplished.

More specific objects and advantages are apparent from the description, in which reference is had to the accompanying drawings illustrating a preferred form of densifying machine embodying the invention.

In the drawings:

Fig. I is a side elevational view of a densifying machine embodying the invention.

Fig. II is a plan view of the machine illustrated in Fig. I.

Fig. III is a fragmentary sectional view, taken substantially on the line III—III of Fig. II.

Fig. IV is a fragmentary somewhat diagram-

matic sectional view, taken substantially on the line IV—IV of Fig. II.

These specific drawings and the specific description that follows merely disclose and illustrate the invention, and are not intended to impose limitations upon the claims.

The main frame of the machine consists of two webbed members 10 and 11, each of which is mounted, by means of bolts 12, on one of two parallel "I" beams 13 which are a portion of the main frame or the building in which the machine is located. A stationary bearing block 14 is mounted on the upper surface of the webbed member 10 by means of bolts 15. A similar stationary bearing block 16 is similarly mounted on the webbed member 11 (see Fig. III). The two bearing blocks 14 and 16 are coaxially located and rotatably support a pressure roll 17.

The pressure roll 17 consists of a hollow cylindrically-shaped member 18 at each end of which there is fastened, by means of stud bolts 19, a hollow trunnion 20. The outer surface of each of the trunnions 20 carries a race 21 which supports the pressure roll 17 on rollers 22 which bear on outer races 23 located in the bearing blocks 14 and 16.

A sliding bearing block 24 (Fig. I) is mounted on ways 25 on the upper surface of the webbed member 10 for movement longitudinally on the member 10. A similar sliding bearing block 26 (Fig. II) is similarly mounted on the upper surface of the webbed member 11. The bearing blocks 24 and 26 rotatably support a pressure roll 27 which is identical in construction and method of mounting to the pressure roll 17.

The rolls 17 and 27 are of uniform diameter throughout their length except at the ends of the rolls where there are located annular shoulders 28 which project above the surfaces of the rolls only a few thousandths of an inch. One of two spacers 29 and 30 is bolted to the side of each of the stationary bearing blocks 14 and 16 and extends horizontally toward the side of the corresponding sliding bearing block. The center lines of the spacers 29 and 30 are located on a horizontal plane on which also lie the axes of the rolls 17 and 27. The spacers 29 and 30 are of such length as to space the rolls 17 and 27 far enough apart so that the shoulders 28 of the two rolls are not permitted to come into contact.

Two horizontally disposed tie rods 31 and 32 (Fig. I) extend through the bearing blocks 14 and 24, the rod 31 being located in that portion of the bearing blocks above the outer races 23.

and the rod 32 in that portion of the blocks below the outer races 23. Nuts 33 are threaded on the ends of the tie rods 31 and 32 extending outside the bearing block 14, and bear against that block. The opposite ends of the tie rods 31 and 32 extend horizontally through a pressure block 34 which is mounted securely on the upper surface of the webbed member 10 by means of bolts 35. Nuts 36 are threaded on the ends of the tie rods 31 and 32 which extend beyond the pressure block 34.

A hydraulic cylinder 31 is provided in the pressure block 34 and its ram 38 is located concentrically with respect to the spacer 29, and with its center line on the same plane as the axes of the rolls 17 and 21. The end of the ram 38 is rounded and bears against a rounded projection 39 on the side of the movable bearing block 24.

Similar tie rods 40 and 41 (Fig. III) are similarly mounted in the stationary bearing block 16 and movable bearing block 26, which are located on the webbed member 11, and pass through a pressure block 42 (Fig. II) similar to the pressure block 34 and are similarly secured thereto. The pressure block 42 has a hydraulic cylinder, and a ram which bears upon a rounded projection on the bearing block 26 and these parts are identical with the parts already described with reference to the pressure block 34.

A four-way swivel-type pipe fitting 43 (Figs. I and III) has its rotating portion mounted in an end plate 44 (Fig. III) on each of the two trunnions 20 which are mounted in the bearing blocks 14 and 24. The fittings 43 are held against rotation by means of brackets 45 which are secured to the fittings 43 and to the blocks 14 and 24.

An outlet pipe 46 is threaded into the stationary portion of each of the fittings 43 and is connected with an inner curved pipe 47 which extends upward to a point near the inner surface of the hollow roll 17 or 21. An inlet pipe 48 is also attached to the fitting 43 and connects to an outer pipe 49 surrounding the pipe 47 in the interior of each of these two hollow trunnions 20. By means of these pipes and fittings, a supply of heating fluid can be circulated through the rolls 17 and 21 to maintain the surface of these rolls at a high temperature. The trunnions supporting the opposite ends of the rolls, which are mounted in the bearing blocks 16 and 26, have attached to their outermost ends a pair of intermeshing bull gears 50 and 51 (Fig. II) which are driven by means of a pinion 52 mounted on a drive shaft 53 which is journaled in a bearing block 54 bolted to the end of the webbed member 11. A housing 55 covers the gears 50 and 51 and the pinion 52.

An auxiliary leveling roll 56 (Fig. II) is mounted in bearing blocks 57 and 58 which are secured to the upper surfaces of the bearing blocks 14 and 16 respectively. The auxiliary leveling roll 56 is fixedly positioned by the blocks 57 and 58 so that its periphery clears the periphery of the roll 17 by a substantial amount (Fig. I). An auxiliary pressure roll 59 is journaled in brackets 60 and 61 which are pivoted on the trunnions of the leveling roll 56 and which permit the pressure roll 59 and its brackets 60 and 61 to swing about the axis of the leveling roll 56. The leveling roll 56 may be rotated, for example by means of a pinion 62 (Fig. II) which is in mesh with the bull gear 50, and the pressure roll 59 may be rotated by means of a chain 63 engaging sprockets 64 and 65 secured to the trunnions of the rolls 56 and 59 respectively. In the case of some materials it is

not necessary to drive the auxiliary rolls 56 and 59 because friction between these rolls and the material will turn them. Cooling fluid is introduced into the interior of the rolls 56 and 59 through inlet pipes 66 (Fig. I) which are secured to swivel-type fittings 67 fastened to the ends of the hollow trunnions of the rolls 56 and 59. The fluid is carried away from the rolls 56 and 59 through outlet pipes 68 (Figs. II and III) which are attached through similar fittings to the opposite trunnions of the rolls. Thermostatically-controlled valves 69 are located in these outlet lines to control the egress of the cooling fluid and thus regulate the temperature of the rolls 56 and 59.

A similar fixed leveling roll 70 and rockable pressure roll 71 are similarly mounted on the bearing blocks 24 and 26 above the roll 21 and may be driven by a pinion 72 in mesh with the bull gear 51. The rolls 70 and 71 are cooled by means of fluid introduced through their hollow trunnions from inlet pipes 73 and carried therefrom by outlet pipes 74.

A pair of scraping knives 75 (Figs. I and IV) extend along the surfaces of the rolls 17 and 21 below the point of closest approach of the rolls for scraping off any material which may adhere to the surfaces of the rolls. Each of the knives 75 is fixed on a rockable shaft 76 to which is secured an arm 77 which carries a weight 78 so located as to press the edge of the knife 75 against the surface of the roll. The shafts 76 are journaled on a cross frame 79 which extends across from the webbed member 10 to the webbed member 11, between the rolls 17 and 21. A rectangularly-shaped chute 80 is secured to the cross frame 79 and its oblong open upper end is located directly beneath the point of closest proximity of the rolls 17 and 21.

A vibratory feeder 81, having a hopper 82, is located above each of the rolls 17 and 21. The vibratory feeders are each mounted on a cross frame 83 which extends across between the bearing blocks 14 and 16 or 24 and 26. The troughs 84 of the feeders 81 are approximately two-thirds as wide as the main portions of the rolls 17 and 21 and their open ends extend close to the fixed auxiliary leveling rolls 56 and 70.

Operation

Fig. IV is a diagrammatic illustration of the operating portions of the machine. The main rolls 17 and 21 are driven by means of the intermeshed bull gears in opposite directions so that their surfaces of closest proximity move toward each other and downward at the same peripheral speed. The auxiliary rolls 56 and 59, or 70 and 71, turn in directions opposite to the main roll with which they are associated.

Pressure is built up in the hydraulic cylinders 31, which forces the movable bearing blocks 24 and 26 toward the stationary blocks 14 and 16. The main rolls 17 and 21 are kept from engagement by the spacers 29 and 30.

Heating fluid is introduced into the interiors of the rolls 17 and 21. The vibratory feeders 81 feed powdered material into the spaces between the leveling rolls 56 and 70 and the main rolls 17 and 21. This material is smoothed into an even layer by the action of the leveling rolls 56 and 70 and is carried forward on the surfaces of the rolls 17 and 21. The material fed by the feeders 81 is fluffy and light, and without the rolls 56 and 70 would not form an even layer on the surfaces of the rolls 17 and 21. These leveling

rolls also slightly compact the material which is fed beneath them. The material then passes beneath the auxiliary rolls 59 and 71 which are floating and the weight of which compacts the material an appreciable amount so that it forms a denser coating on the surfaces of the main rolls 17 and 27. The material then travels with the rotating of the main rolls 17 and 27 until it reaches the space between the main rolls. The pressure in the hydraulic cylinders 37 is built up to a point at which it permits the main rolls to be forced apart only a slight amount by the material being squeezed between them and exerts tremendous pressure on such material. The two layers being carried by the two main rolls are thus merged into one which is greatly densified and compacted.

The temperature of the heating fluid which is introduced into the interior of the main rolls 17 and 27 varies according to the type of fusible molding powder which is being compacted. The temperature should be high enough to bring the powder to a plastic state by the time it passes between the main rolls. The auxiliary rolls 56, 59, 70 and 71 are all cooled to prevent any of the material from sticking to their surfaces. Because of their proximity to the main rolls, they tend to assume the temperature of the main rolls unless they are cooled. The knives 75 are for the purpose of cleaning off the rolls any particles of material which may break away from the main strip of compacted material leaving the pressure rolls, particularly at the edges of the strip. The compacted material enters the chute 80 which leads to a cooled granulating machine where it is cut into granules of the desired size.

The device can be operated satisfactorily in some cases by using only one auxiliary roll, preferably the fixed roll 56 or 70 above each main roll, and omitting the other auxiliary roll from each main roll. However, for most fusible powders, it has been found desirable to employ all of the auxiliary rolls illustrated in Fig. IV in order to cause the heat from the main rolls to fuse all of the material and thus drive out all of the air and other gas and produce a uniformly dense sheet. In any case the main rolls should be substantially horizontal and are preferably driven at substantially the same peripheral speed. The powdered material may be fed to only one of the main rolls if desired.

By forming the material into a relatively dense, compact layer on each of the main rolls 17 and 27, the auxiliary rolls cause the material to be heated rapidly to the temperature of the main rolls before it passes between the main rolls. The material in its initial fluffy powdered form is a very poor conductor of heat, and it would not be heated satisfactorily by contact with the main rolls if it were not compressed on the main rolls by the auxiliary rolls.

Various embodiments of the invention may be devised to meet various requirements.

Having described the invention, we claim:

1. An apparatus for preheating and densifying a fusible powdered material comprising, in combination, a pair of substantially horizontal pressure rolls, each having an internal passage supplied with a heating medium, means for rotating the pressure rolls in opposite directions, powder-feeding means for feeding said material to one of the pressure rolls at a point at which said mate-

rial is carried forward with the surface of the pressure roll, a fixed auxiliary roll located ahead of such point for forming said material into a uniform layer on the pressure roll, and an auxiliary pressure roll ahead of said fixed auxiliary roll for preliminarily compressing said layer, the layer of material being pre-heated as it is carried along by the rotation of the pressure roll, and being fused and densified as it passes between the pressure rolls.

2. An apparatus for preheating and densifying a fusible powdered material comprising, in combination, a pair of substantially horizontal pressure rolls, each having an internal passage supplied with a heating medium, means for rotating the pressure rolls in opposite directions, powder-feeding means for feeding said material to one of the pressure rolls at a point at which said material is carried forward with the surface of the pressure roll, a fixed auxiliary roll having an internal passage supplied with a cooling medium, located ahead of such point for forming said material into a uniform layer on the pressure roll, and a floating auxiliary roll having an internal

passage supplied with a cooling medium, located ahead of said fixed auxiliary roll for preliminarily compressing said layer by its own weight, the layer of material being pre-heated as it is carried along by the rotation of the pressure roll, and being fused and densified as it passes between the pressure rolls.

3. An apparatus for preheating and densifying a fusible powdered material comprising, in combination, a pair of substantially horizontal pressure rolls, each having an internal passage supplied with a heating medium, means for rotating the pressure rolls downward toward one another at substantially the same peripheral speed, powder-feeding means for feeding said material at a point adjacent the top of each of said pressure rolls, a fixed auxiliary roll located ahead of each of such points for forming said material into a uniform layer on each pressure roll, and an auxiliary pressure roll ahead of each of said fixed auxiliary rolls for preliminarily compressing each layer, each of the layers of material being pre-heated as it is carried along by the rotation of the pressure roll, and the two layers being fused and compacted into a single layer as they pass between the pressure rolls.

4. An apparatus for preheating and densifying a fusible powdered material comprising, in combination, a pair of substantially horizontal pressure rolls, each having an internal passage supplied with a heating medium, means for rotating the pressure rolls downward toward one another at substantially the same peripheral speed, means for feeding said material at a point adjacent the top of each of said pressure rolls, a fixed auxiliary roll having an internal passage supplied with a cooling medium, located ahead of each of such points for forming said material into a uniform layer on each pressure roll, an auxiliary pressure roll having an internal passage supplied with a cooling medium, located ahead of each of said fixed auxiliary rolls for preliminarily compressing each layer, by its own weight, and means for applying a substantially constant pressure to the pressure rolls to compress into a single layer the two layers so produced.
